UNITED STATES PATENT OFFICE.

GILBERT MORRISON, JR., OF ELBERTON, GEORGIA.

STOKING MECHANISM.

1,115,004.

Specification of Letters Patent.

Patented Oct. 27, 1914.

Application filed September 17, 1912. Serial No. 720,841.

To all whom it may concern:

Be it known that I, GILBERT MORRISON, Jr., a citizen of the United States of America, residing at Elberton, in the county of 5 Elbert and State of Georgia, have invented new and useful Improvements in Stoking Mechanisms, of which the following is a specification.

This invention relates to improvements 10 in coaling or stoking mechanisms and has particular application to a mechanism of the type set forth employed for coaling the locomotives of railway cars from the tender.

In carrying out the present invention, it 15 is my purpose to provide a coaling or stoking mechanism or apparatus whereby the fuel may be conveyed from the tender to the fire box of the locomotive in such manner as to eliminate the necessity of manual 20 labor usually incident to the coaling of locomotives and similar traction engines. Furthermore, I aim to provide an apparatus of this class by means of which the coal may be automatically fed from the 25 tender to the fire box of the engine and distributed in such fire box and over the burning fuel therein in an even and uniform manner thereby aiding combustion and the burning of the fuel with uni- 30 formity.

A still further object of this invention is the provision of a coaling or stoking mechanism or apparatus which will include devices arranged within the tender or coal 35 car and operated by power, preferably supplied from the locomotive boiler, and an endless traveling conveyer in communication with said devices and designed to carry the coal from the tender to the fire box 40 of the engine and deposit such coal therein, the power or driving mechanism of the stoking apparatus being under manual control.

With the above and other objects in 45 view, the invention consists in the construction, combination and arrangement of parts set forth in and falling within the scope of the appended claim.

In the accompanying drawings, there has 50 been illustrated one preferred and practical embodiment of my invention, and in these drawings; Figure 1 is a fragmentary sectional view through a locomotive tender

or coal car, the latter being equipped with the present invention. Fig. 2 is a top plan 55 view of the stoking apparatus applied to the tender, parts being broken away. Fig. 3 is a front elevation of the tender. Fig. 4 is a fragmentary horizontal sectional view therethrough, parts of the stoking mechanism being shown in elevation taken on the line 4—4 of Fig. 3. Fig. 5 is a horizontal sectional view through the tender taken on the line 5—5 of Fig. 3. Fig. 6 is a trans- 60 verse sectional view through the tender 65 taken on the line 6—6 of Fig. 2, and Fig. 7 is an enlarged sectional view of part of the stoking mechanism showing the distributor. Fig. 8 is an edge view of the 70 distributor.

Similar reference characters designate like parts through out the several views.

Referring now to the accompanying drawings in detail, the cab portion of a locomotive is indicated at A, a portion of 75 the fire box B, while the tender or coal carrying car of the locomotive or engine is indicated at C, the engine and tender being coupled to each other by any well known or preferred form of coupling, as 80 will be readily understood.

W designates the water chamber or compartment of the tender which in the present instance surrounds the coal receiver R. The coal receiver R, in the present instance, 85 tapers downwardly as shown in Fig. 6 and at its bottom or lower portion is provided with a discharge mouth M extending preferably the full length of the receiver.

In accordance with the present invention, 90 a number of coal feeding devices are located within the coal receiver and so correlated as to effectively discharge the coal from the container by way of the outlet mouth M when such devices are in operation. 95

Arranged longitudinally and centrally of the coal receiver R at an appropriate distance above the discharge mouth thereof and secured to the end walls of the receiver in any suitable manner or by any preferred or 100 well known means, is a guard or deflector 1 of substantially triangular outline in cross section and having its apex facing the inlet of the coal receiver. Disposed below the deflector 1 at the marginal edges thereof 105 and arranged longitudinally of the coal re-

ceiver in spaced parallel relation, are agitators 2, 2 of any suitable construction, such agitators being journaled in the end walls of the receiver. Located at each side of the outlet mouth M of the coal receiver at a suitable distance above the same, and outwardly of the agitators 2, 2, is a shaker bar 3 arranged longitudinally of the coal receiver and slidably disposed within a guide 4 and 10 equipped with pins 5 spaced apart and projecting toward the pins on the opposite shaker bar. Mounted beneath the discharge mouth M of the coal receiver R and arranged upon the opposite sides and longitudinally 15 thereof are a pair of feed rollers 6, 6 spaced apart and journaled in the opposite end walls of the tender.

The agitators 2, 2 and the feed rollers 6, 6 are adapted to be rotated to facilitate the 20 discharge of the coal or other fuel from the receiver R, while the shaker bars 3, 3 are designed to be reciprocated to assist in the feeding of the fuel. These several devices are preferably driven simultaneously and 25 from a single source of power which, in the present instance embraces a steam engine E of the reciprocating type fixed to a base or support 7 carried by the forward end of the tender immediately rearwardly of the locomotive cab, the engine being fed or supplied 30 with steam through a conduit 8 equipped with a controlling valve 9 and connected up to the steam dome of the boiler of the engine or other suitable steam carrying pipe. 35 To one extremity of the crank shaft 10 of the engine is keyed a bevel gear 11 and disposed at the opposite sides of such bevel gear and meshing with the teeth thereof are similar pinions 12 and 13 each keyed to a shaft 40 14 journaled in suitable bearings upon the base or support 7 and carrying a sprocket wheel 15, and keyed to the end of the crank shaft 10 beyond the bevel gear 11, is a sprocket wheel 16. The forward extremities 45 of the agitators 2, 2 terminate beyond the respective end wall of the tender in stub shafts and keyed or otherwise secured to each stub shaft of the respective agitator is a sprocket wheel 17. Likewise, the forward 50 extremities of the feed rollers 6, 6 terminate beyond the respective end wall of the tender in stub shafts and to these last-mentioned stub shafts are keyed or otherwise fastened sprocket wheels 18, 18, suitable idle rollers 55 19, 19 being carried by the end wall of the tender outwardly of the wheels 18, 18 and at the relatively opposite sides of the centers of such sprockets, for a purpose which will presently appear. Trained over the sprocket 60 wheel 16 and engaging the similar wheels 17 and 18 and running around the idle rollers 19, 19, is an endless traveling chain 20 engaging the sprocket wheel 17, 17 and 18, 18 in such manner as to rotate the agitators and 65 feed rollers in relatively opposite directions

to one another. If desired, a suitable clutch may be employed to connect and disconnect the sprocket wheel 16 to and from the crank shaft 10 respectively. In utilizing a steam engine for the driving of the mechanism, 70 however, a clutch mechanism need not be employed as the engine is at all times under the control of an operator or attendant by means of the controlling or throttle valve 9.

As before stated, the shaker bars 3, 3 are 75 reciprocated to assist in discharging the fuel or coal from the receiver, and to this end a shaft 21 is made use of and journaled within a bracket 22 secured to the forward end of the locomotive tender, with respect to the locomotive, and the opposite ends of such shaft 21 are equipped with crank arms 23, 23 connected to the respective shaker bar 3 through the medium of a link 24 or the like. This shaft 21 is adapted for rotary 80 movement within its bearings so as to impart reciprocatory motion to the shaker bars and for this purpose has keyed thereto a sprocket wheel 25 and over the sprocket wheel 25 and the similar wheel 15 upon the 85 shaft of bevel gear 13, is trained an endless chain 26 by means of which motion from the bevel gear 11 is, through the medium of the shaft 14 and sprocket 15, transmitted to the shaker bar shaft 21, thus reciprocating the bars in the stoking operation. 90

The feed rollers 6, 6 are preferably mounted in yieldable bearings so that such rollers may be moved relatively toward and away from each other so that in the event of relatively large lumps of coal entering the space between the rollers, such coal may be discharged without mutilating or otherwise injuring the rollers and their bearings. To effect this relative movement of the rollers 6, each end of each roller is, as shown in Fig. 3, journaled in a bearing slidably disposed within a slot or guide way 27 and disposed intermediate the bearing and one wall of the slot or guide way is a tension device such as an expansion spring 28. Thus, it will be seen that the rollers 6, 6 may be moved relatively to each other should a relatively large lump of coal enter 105 the space between the same. 110

The part of the mechanism so far described relates particularly to the portion of the stoking mechanism for discharging the coal from the coal receiver of the tender. Subsequent to the discharge of the fuel or coal from the receiver, the same is deposited upon an endless traveling conveyer and by means of such conveyer carried to the fire box of the engine or locomotive to facilitate the feeding of the fuel automatically. To accomplish this, an endless traveling conveyer 29 is trained over a roller 30 journaled in or carried by the end wall of the tender opposite from the wall carrying the engine platform 7, and a roller 31 journaled in the 115 120 125 130

opposite side walls of a frame 32, the last-mentioned roller being disposed normally in proximity to the fire door of the furnace fire box. The conveyer 29 is disposed immediately below the feed rollers 6 and extends the full length of such rollers, and the supporting frame 32 of the forward portion thereof is pivoted as at 33 to a bracket 34 of a configuration conforming to the cross 5 sectional contour of the frame and secured to the proximate end wall of the tender. Journaled in the forward end of the bracket 34 and forming the pivotal connection between such bracket and the frame 32, is a 10 shaft 35 to which is keyed or otherwise secured a supporting drum 36 equipped at its opposite extremities with sprocket wheels 37 each of which engages a chain or the like 15 secured to the adjacent marginal edge of the conveyer 29 or formed integral with such conveyer, as desired. This shaft 35 in addition to forming the pivot of the frame 32, acts as the drive shaft of the drum 36, the sprocket wheels 37 and consequently the 20 conveyer and for this purpose has keyed thereto outwardly of the conveyer, a sprocket wheel 39 over which, and the sprocket wheel 15 on the shaft 14 of the bevel gear 12, is trained an endless chain 40. Thus, it 25 will be noted that the conveyer is provided with a central drive, such being preferable incident to the pivotal connection between the supporting frame 32 and the bracket 34. 30

It will be noted that the frame 32 is inclined upwardly from the bracket 34 and the forward extremity thereof terminates in an abutment wall 41 designed to snugly engage the marginal edges of the door opening of the fire box B of the locomotive and 35 resting against such wall under pressure, incident to the upward inclination of the frame. Pivotedly mounted upon the upper portion of such abutment wall, as at 42, is a door 43 adapted to be opened and closed 40 to establish communication between the conveyer 29 and the fire box and cut off communication between such conveyer and fire box. This door is under manual control and 45 is designed to gravitate to a closed position and is opened through the medium of a horn 50 44 secured to or integral with one end of a shaft 45 journaled in brackets 46 and connected at its opposite end to an arm 47 to the free extremity of which latter is pivotally connected a rod 48 also pivotally connected at its free end as at 49 to an operating 55 lever 50 provided with the usual locking dog and movable about a quadrant 51 secured upon a bracket 52 fastened in any suitable manner 60 to the adjacent portion of the respective end of the tender. From this construction, it will be noted that by means of the lever 50, the rod 48 may be actuated to impart movement to the horn 44 and so open the door 43, the locking dog being adapted to engage

the notches in the quadrant 51 to hold the door in open position, the release of the operating lever 50 retracting the horn 44 and permitting the door to gravitate to closed position. 70

In the practice of my invention, I have found it desirable to provide means whereby the coal or other fuel upon the conveyer may be distributed evenly and uniformly within the fire box B and over the fuel 75 therein so as to aid combustion and for other similar purposes, and to this end I have pivotally connected as at 53 to the bottom of the supporting frame 32, a distributer 54 of preferably concavo-convex outline in longitudinal section and having its convexed portion designed to receive the coal from the conveyer 29, so as to effect the even distribution of such coal. This distributer 54 is adapted to be oscillated or moved from 80 side to side about its pivotal connection 53. In order to apply or impart such oscillating movement to the distributer, the latter is driven from an appropriate part of the driving mechanism of the stoker or coaling 85 mechanism, for instance, the driving shaft 35 of the conveyer, the latter being equipped at one extremity with a crank arm 55 to which is pivotally connected one extremity of a pitman 56, the opposite extremity of 90 the latter being pivotally connected to a bell crank lever 57 pivoted at its bight as at 58 and having its free arm connected to the distributer 54 through the medium of a link 59. Thus, in the movement of the driving 95 shaft of the conveyer, oscillatory motion will be imparted to the distributer 54 to enable the distribution of the coal in the manner aforesaid. 100

In the present instance, I have shown my 105 invention as applied to a railroad locomotive or hauling engine, and in this connection I desire to have it understood that my invention is not limited to any particular type of road engine, as the same may be 110 applied to any form of traction or hauling engine depending upon coal or the like fuel for its propulsion, and while I have herein shown and described one particular form of my invention by way of illustration, I desire to have it understood that I do not confine myself to the exact details of construction herein described and delineated, as modification and variation may be made within the scope of the claim and without 115 departing from the spirit of my invention. 120

I claim:

In combination, a locomotive fire box having a fuel feed opening therein, a tender; a fuel conveyer frame pivotally supported at 125 one end upon said tender and inclined upwardly from the tender, an abutment wall on the other end of said frame engaging the marginal walls of the fuel feed opening under pressure, a door pivoted upon the fire box 130

end of said frame, said door being adapted
to close said opening, means for opening
said door, and a distributer carried by the
last-mentioned end of said frame and dis-
posed within the fuel feed opening of said
fire box.

In testimony whereof I affix my signature
in presence of two witnesses.

GILBERT MORRISON, JR.
